UNITED STATES PATENT OFFICE.

RUSSELL E. BANNON, OF SPRINGFIELD, MASSACHUSETTS.

HOLDER FOR NURSING BOTTLES.

Application filed August 26, 1920. Serial No. 406,243.

To all whom it may concern:

Be it known that RUSSELL E. BANNON, a citizen of the United States of America, residing at Springfield, in the county of 5 Hampden and State of Massachusetts, has invented certain new and useful Improvements in Holders for Nursing Bottles, of which the following is a specification.

This invention relates to improvements in 10 supports for nursing bottles and its leading object is to provide a support which will hold a nursing bottle on a crib, basket or other device in which a child or infant may be arranged, in such manner that the nursing 15 bottle will be supported in an inclined position to prevent the infant from drawing in air and getting the colic and capable of being swung outwardly from feeding position.

20 Another object of the invention is to provide a device which can be used for supporting all types and sizes of bottles and which has an overlying yoke capable of supporting the bottle at different inclinations with respect to the holder and the crib or the like.

With the above and other objects in view this invention relates to certain new and useful constructions, combinations and arrangements of parts, clearly described in the following specification and fully illustrated in 30 the accompanying drawings, in which:

The figure is a perspective view of the device illustrating a bottle supported in drinking position thereby.

35 Referring to the accompanying drawings 5 designates a side bar of a crib to which is attached a bracket formed of wire and consisting of a bar 6 having lugs or terminal portions provided with eyes 8 secured in place to the bar 5 by means of screws 7 or the like. The central portion of the bar 6 between the terminal eyes thereof is slightly spaced from the adjacent face of the bar 5. This bracket construction supports a frame 40 consisting of bars 9 and 10 which are connected to each other by means of a loop 12 preferably disposed at an angle relative to the bars 9 and 10 to receive the tapered neck of the nursing bottle. The lower portions 45 of the bars 9 and 10 are formed with registering eyes 13 which are connected together by means of a tie rod 14 having its ends substantially bound around said eyes as will be readily understood. The bars 9 and 10

are further provided with outwardly offset 55 closed loops providing eyes 9^b disposed in registration with each other and which are connected to each other by means of a tie rod 22.

A U shaped frame consisting of side bars 60 18^a and 19^b is pivotally connected to the eyes 9^b to have a swinging movement thereon and this U shaped frame provides a loop 20 on its outer end which forms a pocket for the upper end of the nursing bottle and a second 65 pocket 21 located inwardly thereof, whereby the nursing bottle may be disposed in various angular positions.

Any nursing bottle whether cylindrical or oval in cross section can be supported on 70 the holder with the nipple within convenient reach of the infant. The holder will support the nursing bottle so that the milk or other liquid food contained therein will always occupy a position immediately above the 75 nipple and the air in the nursing bottle will not be drawn in by the infant during the feeding. The inclination of the nursing bottle may be adjusted by positioning it in either of the pockets 20 or 21 of the adjusting 80 yoke 17 and when so adjusted the hydrostatic pressure of the milk or liquid food may also be varied so that the flow can be regulated to some extent.

When the infant is finished feeding the 85 holder may be swung outwardly of the crib or the like so as to be out of the way of the infant.

Having described my invention, I claim:

1. A holder for nursing bottles or the like 90 consisting of a bracket adapted to be secured to the side of a crib, a frame swingingly supported by the bracket and provided with an opening through which the neck of a bottle may extend downwardly to support 95 a nipple below the frame with the bottle in inclined position, and a yoke pivotally connected with the frame and provided with means for adjusting the inclination of the bottle supported.

2. A bottle holder consisting of a frame provided with a laterally disposed loop adapted to receive the neck of an inverted bottle, and a yoke pivoted to the frame above the loop and provided with means for supporting the bottle in more than one inclined position.

3. A nursing bottle holder consisting of a

2
frame provided with a laterally disposed rigid loop designed to receive the neck of an inverted nursing bottle, a second loop hingedly secured to the frame above the first loop and provided with a plurality of pockets for receiving the base end of the bottle, and means for supporting the bottle

holder in depending position on the side of a crib arranged to permit said holder to swing upwardly and outwardly thereof.

10

Signed by me at Springfield, Massachusetts.

RUSSELL E. BANNON.
